PROCESS OF NITRATING KEROSENE

Fred Fiala, Sr., Cleveland, Ohio

No Drawing. Application September 3, 1948, Serial No. 47,747. In Czechoslovakia July 23, 1948

1 Claim. (Cl. 260—644)

2

1 This invention relates to processes for treating hydro-carbons and particularly for nitrating kerosene.

Conducive to a clearer understanding of this invention it may be well to point out that crude oil distillates may be nitrated by concentrated nitric acid or by a nitrating mixture, in which operation oxidation products and in hot condition also carbonic acids are produced in addition to nitro-paraffines. Monoderivatives are soluble in the initial substance whereas dinitro- and trinitro-derivatives pass into the acid. The lower members of the paraffin series are liable to explode, in particular when heated. For this reason the said derivates have not been practically used up to now.

According to the invention it has been found that by a simple nitration of kerosene in cold condition, wherein the kerosene is thoroughly mixed with a small quantity of concentrated nitric acid and then left standing for several days, whereupon it is drained off and washed by a weak solution of a base, an extremely well suited solvent and purifying agent is obtained, having a pleasant smell and adapted to be distilled without undergoing decomposition and even without the danger of explosion. Compared with the initial kerosene it has even a higher flash point and ignition-point.

An example of carrying out the invention in practice will now be described.

To one litre of kerosene having a boiling range of 100 to 350° C., 3-5 cm.³ of nitric acid of a concentration of 40 to 45° Bé. are added. The obtained mixture is thoroughly agitated and left at rest for at least 7 days. During this time the surplus of nitrogenous and other free substances is separated, said substances being deposited at the bottom of the container. The crude nitrated kerosene is drained off into another container and washed with a 1% solution of sodium bicarbonate of which about one tenth of the volume of the treated kerosene is sufficient. The latter is thus freed from the remaining, still free not-combined nitrogenous substances, which pass into the aqueous solution, which after a half-hour

standing are deposited on the bottom. In this way clean nitrated kerosene of lemon color is obtained which is drained off and serves then as solvent, purifying agent and the like, and which after its solvent power has been exhausted may be purified by distillation to make it suitable for further use.

In determining the physical properties the following values have been found.

10

		Before Nitration	After Nitration
15	Flash-point	°C.	67
	Ignition-point	°C.	74
	Specific weight		0,8270 0,8275

Having thus disclosed the invention in its preferred form; it is to be understood that there may be other forms or modifications of the invention which should also be construed to come within the scope of the appended claim.

I claim:

25 The process of nitrating kerosene which consists in thoroughly mixing from 3 to 5 cm.³ of nitric acid of a concentration of 40 to 45° Bé. to one litre of kerosene having a boiling range of from 100 to 350° C. at normal room temperature at atmospheric pressure, the leaving of the same at rest for a time interval to permit the nitrogenous and other free substances to deposit at the bottom and the draining off of the remainder and washing the same with a relatively weak base solution.
